HENRY C. SEARS.

UNITED STATES PATENT OFFICE.

HENRY C. SEARS, OF BOSTON, MASSACHUSETTS.

DESIGN FOR A VEHICLE.

SPECIFICATION forming part of Design No. 13,329, dated October 3, 1882.

Application filed August 9, 1882. Term of patent 14 years.

To all whom it may concern:

Be it known that I, HENRY C. SEARS, of Boston, in the county of Suffolk and State of Massachusetts, and a citizen of the United States, have made a certain new and Improved Design for Vehicles, of which the following is a full, clear, and exact description, reference being had to the accompanying photographs, in explaining the nature of the design, in which—

10 Plate 1 represents a perspective view of the front and side of the vehicle, and Plate 2 a perspective view of the back thereof.

The class of vehicles to which the improved carriage relates is known as "cabs;" and the design has for its especial features the front panels and shape of the front of the vehicle, and the arrangement and shape of the driver's seat, the sides and windows, the rear panels, the roof, and the body as a whole, as hereinafter 20 specified.

The front A of the cab has the panels A' on either side of the driver's seat a, which projects from the front wall thereof, substantially as shown in the photographs, and they and the 25 seat are of the shape or substantially the shape therein indicated. The front also has the recess a' above the driver's seat, which extends therefrom to the top of the vehicle. The front also has the windows a², or spaces for windows, 30

35 on either side of the recess a', and also, if desired, ventilating-apertures a³ above the windows. The remaining portion of the front is shaped substantially as shown in Plate 1, which also represents very well all the features of this portion of the design. Each side B has the panel or section b a little rounded or drawn in somewhat at the lower edge thereof, and is well shown in Plate 1 and by outline in Plate 2. The front edge of this panel is curved down 40 wardly and forwardly, as represented at b', Plate 1. Below the panel b the body is decreased in width, substantially as shown in the said plates, there being, as shown, the substantially horizontal portion b², which extends inwardly from the lower edge of the panel b, and the under section, b³, which extends from the

inner edges of the sections b² downwardly and inwardly to the bottom of the body. The upper portion of the side preferably has the two sections b⁴ b⁵ and the windows b⁶, or space for 50 the glass; but this portion of the design may be modified to include two or more windows, if desired. The rear or end of the vehicle has the plain panels c on either side of the door, the window e' above the panels, and the doors 55 c², rounded outward, having the windows or glasses c³. The outline of the panel c and of the back generally is represented in Plate 2. The shape of the top or roof of the vehicle is well represented in the two plates. 60

Having thus fully described my improved design, I claim and desire to secure by Letters Patent of the United States—

1. The design for a vehicle-front, substantially as shown and described. 65

2. The design for the upper section of the vehicle-front, which includes the portion a' of the vehicle, substantially as shown and described.

3. The design for a vehicle, comprising the 70 driver's seat a and the panels A' of the vehicle, substantially as shown and described.

4. The section of the front, comprising the portion a' and the windows or openings a² upon either side thereof. 75

5. The design for the side of a vehicle, substantially as shown and described.

6. The design for the back of a vehicle, substantially as shown and described.

7. The design for a cab-roof, substantially as 80 shown and described.

8. The design for a side panel, substantially as shown and described.

9. The design c for an end panel, substantially as shown and described. 85

10. The design for a vehicle-body, substantially as shown and described.

HENRY C. SEARS.
